DESIGN FOR A HANDLE FOR PANS

Richard F. Krause, Massillon, Ohio

Application December 6, 1934, Serial No. 54,303

Term of patent 14 years

To all whom it may concern:

Be it known that I, Richard F. Krause, a citizen of the United States, residing at Massillon, in the county of Stark and State of Ohio, have invented a new, original, and ornamental Design for a Handle for Pans, of which the following is a specification, reference being had to the accompanying drawing, forming part thereof.

Fig. 2, a side elevation of the handle shown in Fig. 1;

Fig. 3, a bottom plan view of the handle; and Fig. 4, a section taken on the line 4—4, Fig. 2.

I claim:

The ornamental design for a handle for pans, as shown.

RICHARD F. KRAUSE.
